UNITED STATES PATENT OFFICE

EVAN EDWARD CANNON, OF BEAUMONT, TEXAS

MECHANICAL VACUUM

Application filed February 3, 1931. Serial No. 513,227.

This invention relates broadly to freezer cases, refrigerators, and such types of refrigerating counters such as meat cases and the like used in stores.

A primary object of the invention is to provide means for producing a mechanical vacuum capable of application to such freezer cases, meat display cases and the like.

With the above and other objects in view, the invention consists in the novel arrangement, combination, and construction as detailed in the accompanying drawings and hereinafter more explicitly described.

In the accompanying drawings forming part of this specification:

Figure 1 is a perspective view of a meat display counter embodying the features of the present invention.

Figure 2 is a fragmentary detail sectional view taken through a portion of the counter for clearly illustrating the invention.

Figure 3 is a detail sectional elevational view of a valve forming part of the invention.

Figure 4 is a longitudinal sectional view through the valve per se.

With reference more in detail to the drawings, it will be seen that the reference character C designates a meat counter or the like, and according to the present invention is provided with a vacuum at the front and top thereof.

In forming the vacuum, the wall of the counter is provided with a suitable opening. Lining this opening is a substantially frame like liner formed from a strip of metal, the liner being designated by the reference character 5. At the inner end thereof the lining frame 5 is provided with a retaining flange 6 that is preferably provided with beveled faces 7 and 8 respectively. Fitting conformably within the liner 5 is a frame like member 9 formed of rubber or analogous material. The member 9 is channel shaped in cross section and is provided at opposite ends with the flanges 10 and 11 respectively. Preferably, the oppositely disposed, vertical portion of the member 9 tapers from the bottom to the upper portion of the member, so that the upper portion of the member 9 is of a width slightly less than the width of the

lower horizontal portion of said member 9. The member 9 provides insulation for the device as will be apparent.

Arranged within the confines of the member 9, and disposed against the inner face of the flange 10 of said member, is a pane or sheet of glass 12. The pane 12 is confined between the flange 10 and an adjacent side of a spacer member 13. Spacer member 13 is in the nature of a frame like structure 55 extending along the marginal edges of the pane 12, and on its inner circumferential face is provided with a groove 14. What may be termed an insert or spreader 15, is inserted within the groove 14. The insert 15 is somewhat wedge shaped in cross section as illustrated and is retained within the groove 14, the medium of fastening elements such as screws 16 passing through the spreader 15, spacer 13, insulation rubber 9, liner 5, and into the material of the counter C.

A second vertical transparent panel 12a is disposed in the opposite side of the spacer 13 and disposed in spaced parallelism to the panel 12. The panel 12a is anchored in position between the spacer 13 and a second sectional spacer, that includes complementary sections 16 and 17 respectively. The sections 16 and 17 are formed of rubber or kindred material.

The section 16 at one end thereof is provided with a flange 18 contacting an adjacent face of the pane 12a and urged against the said face of the pane, through the medium of an insert or spreader 19 that is anchored 85 in position through the medium of fastening elements 20 similar to the fastening elements 16 and passing through the member 19 sections 16 and 17, and through the elements 9, 5, and the material of the counter. The member 19 fits, and is wedged between flange 18 of section 16, and flange 21 of section 17. Overlapping portions of the sections 16 and 17 are beveled as shown, and opposite vertical portions of the sections decrease in width 95 as they continue toward the upper portion of the respective sections as shown in Figure 2.

An obliquely disposed transparent pane or panel 12b is anchored in position between the 100

flange 21 of section 17, and the flange 11 of the insulation strip 9.

An element 22 formed of rubber and functioning in the nature of a gasket, is disposed 5 against the flange 11 and a marginal portion of the transparent panel 12b, the gasket 22 being provided with a notch 23 for accommodating the flange 11. Above the notch, the gasket 22 is cut away to provide a shoulder 10 for accommodating an extended portion of a retaining flange or molding 24. Molding 24 is anchored in position through the medium of suitable fastening elements 25.

Preferably, the transparent panels are cemented 15 to the flanges 10, 18, 21 and to the spacer 13 and gasket 22. Thus it will be seen that between adjacent panels are provided vacuum chambers, a relatively narrow vacuum chamber 26 being provided between the 20 parallel panels 12 and 12a, and a relatively wide vacuum chamber 27 being provided between the panels 12a and 12b, the chamber 27 progressively decreasing in width upwardly.

25 For each vacuum chamber there is provided a valve, the same including a cylindrical body 28 reduced at one end as at 29. The body 28 is provided with an axial bore 30 continuing through the extension or reduced end 29. At 30 its opposite end the body 28 is counterbored as at 31 and at the inner end of the counter bore is provided with a conical valve seat 32. A valve core 33 has its beveled end normally engaged with the seat 32 through the medium 35 of a coil spring 34. One end of the spring 34 bears against the valve core 33 and the other end of the spring bears against one end of an axially bored plug 35 threaded within the counter bore 31.

40 In operatively positioning the valve with respect to chamber 26, for example, it will be seen that the reduced end 29 of the valve body extends through a portion of the insert or spreader 15, and at said end is provided 45 with an annular flange 36 that is adapted to be embedded in the insulation rubber 9. Remote from flange 36, a flanged hexagonal nut 37 is screwed on to the threaded end 38 of the body 28, and the flanged nut 37 fits within 50 a recess provided therefor in a portion of an end wall W of the counter C. The threaded end portion 38 at its extremity extends into a pocket 39 provided in said one wall W, and to this free end portion, may be threaded 55 the hose of a suitable suction pump for drawing air from the chamber 26.

Pocket 39 is normally closed through the medium of a suitable hinged door 40. The valve for the chamber 27 is mounted in identically the same manner as described with reference to the valve or chamber 26.

For the purpose of reinforcing the glass panels when a vacuum has been created between two adjacent panels there is provided 60 a suitable spreader 35, of glass or other suit-

able material, the ends of the spreader being cemented to the panels as shown. A spreader 35 may be arranged in each of the chambers 26 and 27.

It is also to be apparent, that the adjacent 70 chambers 26 and 27 may have their structure duplicated in the top or table part of the counter, or in any other wall of the counter.

Even though I have herein shown and described the preferred embodiment of the invention, it is to be understood that the same is susceptible of changes, modifications and improvements coming within the scope of the appended claims.

Having thus described my invention, what 80 I claim as new is:

1. A counter or the like comprising a wall having an aperture having a strip of metal lining the aperture, a pair of relatively spaced panels arranged within the opening and cooperating with the lining strip for closing said opening, a strip of rubber inserted between the edges of said panel and the corresponding portions of said lining strip, and wedge means for spacing said panels located between said panels and contacting the latter adjacent the marginal edges thereof.

2. A counter or the like comprising a wall 95 provided with an aperture and having a strip of metal lining the aperture, a pair of relatively spaced panels arranged within the aperture and cooperating with the lining strip for closing said aperture, a strip of rubber inserted between the edges of said panels and the corresponding portions of said lining strip, a spacer member between said panels and contacting the latter adjacent the marginal edges thereof, said spacer member provided with an internal groove, a wedge member fitted within the groove, and fastening elements passing through said wedge member, said spacing member, said rubber strip and said metallic lining strip being embedded 100 in said wall.

3. In a device of the character described, the combination of a wall having an aperture therein, a strip of metal lining the aperture and provided on one end thereof with a flange, an insulation strip of rubber arranged within the confines of said metal lining, said insulation strip being channel shaped in cross section, a plurality of relatively spaced panels having their marginal edges fitting within the channel of said rubber strip, and wedge means arranged within the channel of said insulating strip and spacing said panels.

4. In a device of the character described, the combination of a wall having an aperture therein, a strip of metal lining the aperture and provided on one end thereof with a flange, an insulation strip of rubber arranged within the confines of said metal lining, said insulation strip being channel shaped in cross section, a plurality of relatively spaced pan-

els having their marginal edges fitting within the channel of said rubber strip, wedge means arranged between adjacent panels for spacing said panels, and a valve member supported in the wall and having one end thereof opening into a space between adjacent panels, and having its opposite end adapted to be coupled to a suction hose.

5. A counter or the like including in combination a wall provided with an aperture, a plurality of spaced panels closing said aperture, flanged rubber strips disposed between the panels, and wedge means urging the flanges of said strips into contact with the

10 panels.

6. In combination, a wall having an aperture, a pair of spaced transparent panels substantially closing said aperture, an expandable member arranged between said panels

20 and wedge means for laterally expanding said member for urging the same into lateral contact with said panels.

7. A device of the character described comprising in combination a wall having an aperture therein, spaced panels substantially closing said aperture, a valve arranged in said wall, and having one end opening into the space between said panels and having its opposite end adapted to be connected to a suction hose.

In testimony whereof I affix my signature.
EVAN EDWARD CANNON.
